FLUORESCENT LAMP FIXTURE

Barry Cohen, 455 Wayland Ave.,
Providence, R.I. 02906

Filed May 1, 1967, Ser. No. 6,893

Term of patent 14 years

(Cl. D48—20)

FIG. 3

FIG. 4

FIG. 5

FIG. 1 is a perspective view of a fluorescent lamp fixture showing my new design;

FIG. 2 is a side elevational view thereof;

FIG. 3 is a top plan view thereof;

FIG. 4 is a rear elevational view thereof; and

FIG. 5 is a bottom plan view thereof.

The broken line showing of a fluorescent lamp and a bracket is for illustrative purposes only.

What is claimed is:

The ornamental design for a fluorescent lamp fixture, as shown and described.
